UNITED STATES PATENT OFFICE.

BENJAMIN J. ROSEWATER, OF EUREKA SPRINGS, ARKANSAS.

TRAFFIC SIGN.

Application filed February 8, 1927. Serial No. 166,745.

This invention relates to a traffic sign adapted to be placed at street intersections, or at other places along the highway, and adapted to display advertising matter, as well as suitable traffic directions.

The object of the invention is to provide a device of this character in which the traffic directions remain stationary, while the advertising matter revolves fast enough to attract attention, but not so fast but that it may be easily read. An electric light is provided for illuminating the signs, and this may be enclosed by a globe made up of differently colored sectors or zones, and preferably rotated more rapidly than the advertising matter. The desired rotation is effected by suitable mechanical means which may be driven by wind, or by some other source of power.

The specific construction of the invention, together with its objects and advantages will be more particularly explained in connection with the accompanying drawing illustrating the same.

In the drawing:

Figure 1 is a vertical sectional view of the invention.

Figure 2 is a vertical sectional view of the upper part of the invention on an enlarged scale with parts broken away.

Figure 3 is a horizontal section taken substantially on the line 3—3 of Figure 2.

The structure, which comprises my invention, is mounted on a tubular mast 5, which is supported in a suitable base 6 of concrete or the like. Suitable traffic directions are inscribed on strips or plates 7 and 8 secured to the upper part of the mast. Below these traffic directions, spaced collars 9 and 10 are secured to the mast, and are formed with opposed channel-shaped flanges 11 and 12 respectively, carrying ball bearings 13, which serve to rotatably support a frame 14 adapted to carry advertising matter. The frame 14 is made up of a plurality of radial wings 15, preferably rectangular in shape, and connected together by rings 16, mounted in the ball bearings 13 and formed with integral projections 16^a in which the wings are secured. Panels 17 of sheet metal or other suitable material are carried by the wings 16 and are adapted to bear advertising matter. The outer strips 15^a of the wings 15 may be detached so that the panels 17 may be removed for relettering. Ornamental scroll work 15^b may be also car-

ried by the wings. The frame 14 may be arranged so as to be rotated by the wind, or by some other source of power.

A conduit 18 extends through the base 6 and upwardly through the mast 5, and is provided at its upper end with a socket 19 for receiving an electric light bulb 20, which is illuminated through the medium of wires 21 extending through the conduit. A ball race 22 is secured to the upper end of the mast 5, and contains bearings 23 which rotatably support a flanged member 24 to which is secured a globe 25 enclosing the light bulb 20. A depending sleeve 26 is secured at its upper end to the member 24, and extends downwardly within the mast 5. A pinion 27 is secured to the lower end of the sleeve 26, and is provided with a downwardly projecting hub 28, which is supported by ball bearings 29 within a ring member 30 secured in the mast 5, adjacent the flanged collar 11.

The mast is provided adjacent the pinion 27 with a slot 31, through which a gear 32 extends into driving relation to the pinion. The gear 32 is rotatably supported by a spindle 33, which is mounted at its lower end in a boss 34 projecting upwardly from the collar 11. The upper end of the spindle 33 is mounted in a member 35, suitably secured to the mast 5. An internal ring gear 36 is secured by brackets 37 to the frame 14 in driving relation to the gear 32.

As illustrated in Figure 1, the globe 25 may be made up of a plurality of differently colored sectors or zones, as for example, sector 38 colored green, sector 39 colored red, and sector 40 colored yellow, so that a varying succession of colors will be displayed as the globe revolves. To intensify the effect, a reflector 41 may be mounted above the globe 25, and supported in any suitable manner, as for example, by brackets 42 secured to the sign bar 8.

It will be understood that the sign bars 7 and 8 always remain stationary, and are inscribed with suitable signs or traffic regulations, while the advertising sheets 17, carried by the frame 14, revolve slowly, and the various wings 17 are successively presented to view. Through the medium of the internal ring gear 36, spur gear 32 and pinion 27 the globe 25 rotates at a comparatively rapid rate, and an attractive succession of colored lights are presented to view, which will call attention not only to the traffic signs

and regulations, but to the advertising matter beneath the same.

While I have shown and described the invention in considerable detail, it is to be understood that the same is not limited to this exact construction, but the form, arrangement and relative proportions of the various elements thereof may be considerably modified without any material departure 10 from the salient features of the invention as claimed.

What is claimed is:

1. In a device of the character described, a stationary tubular mast, direction signs 15 secured thereon, a lamp supported near the top of the mast, an advertising device rotatably supported on the mast, a globe of distinctive design enclosing said lamp, a member rotatably mounted at the upper end of 20 the mast and supporting said globe, a sleeve secured to said member and depending within the mast, and means operatively connecting the advertising device to said sleeve to rotate the latter, together with the 25 globe, at a greater angular velocity than the advertising device.
2. In a device of the character described, a stationary tubular mast, direction signs secured thereon, a lamp supported near the 30 top of the mast, an advertising device rotatably supported on the mast, a globe of distinctive design enclosing said lamp, a member rotatably mounted at the upper end of the mast and supporting said globe, 35 a sleeve secured to said member and depending within the mast, a pinion secured to the lower end of said sleeve and having

a downwardly projecting hub, bearings for said hub located within the mast, said mast having a slot in one side adjacent said pinion, a spur gear projecting into said slot and meshing with the pinion, supporting members on which said spur gear is rotatably mounted, said supporting members being secured in fixed relation to the mast, 40 an internal ring gear concentric with said pinion and meshing with the spur gear, and brackets securing said ring gear in fixed relation to the advertising device, whereby said globe is rotated by and at a greater angular velocity than said advertising device. 45

3. In a device of the character described, a stationary tubular mast, direction signs secured thereon, a lamp supported near the top of the mast, an advertising device rotatably supported on the mast, a globe of distinctive design enclosing said lamp, a reflector supported by and in fixed relation to the direction signs and above said globe so as to intensify the illumination of the direction signs and the advertising device, a member rotatably mounted at the upper end of the mast and supporting said globe, a sleeve secured to said member and depending within the mast, and means operatively connecting the advertising device to said sleeve to rotate the latter, together with the globe, at a greater angular velocity than the advertising device. 55

In testimony, that I claim the foregoing 60 as my own, I have hereto affixed my signature.

BENJAMIN J. ROSEWATER.
